UNITED STATES PATENT OFFICE.

LELAND G. YOUNG, OF MUSCATINE, IOWA.

VERMIN-TRAP.

1,223,016.

Specification of Letters Patent.

Patented Apr. 17, 1917.

Application filed January 15, 1917. Serial No. 142,481.

To all whom it may concern:

Be it known that I, LELAND G. YOUNG, a citizen of the United States, residing at Muscatine, in the county of Muscatine and 5 State of Iowa, have invented a new and useful Vermin-Trap, of which the following is a specification.

This invention relates to traps for catching vermin such as found in chicken houses 10 and the like.

One of the objects of the invention is to provide a simple, compact and efficient device of this character which can be applied readily to a roost and which provides hiding 15 places for the vermin where they will congregate and subsequently be removed and destroyed, the removable portion being simple and inexpensive so that it can be replaced at slight cost.

20 With the foregoing and other objects in view which will appear as the description proceeds, the invention resides in the combination and arrangement of parts and in the details of construction hereinafter described 25 and claimed, it being understood that changes in the precise embodiment of the invention herein disclosed, can be made within the scope of what is claimed, without departing from the spirit of the invention.

30 In the accompanying drawings the preferred form of the invention has been shown.

In said drawings:—

Figure 1 is a plan view of the device applied to a perch or roost.

35 Fig. 2 is a section on line 2—2 Fig. 1.

Fig. 3 is a section on line 3—3 Fig. 1.

Referring to the figures by characters of reference 1 designates an ordinary perch or roost such as commonly employed in chicken 40 houses and the like and arranged thereon near one end is an ordinary nail 2 the head of which is supported above the top surface of the perch. Extending from the other end of the perch is a stem 3 having a hook 4 at 45 its upper end.

The device constituting the present invention comprises an elongated strip 5 the sides of which are preferably, though not necessarily beveled as indicated at 6, and formed 50 longitudinally within the bottom face of this strip is a channel 7 designed to receive a strip of corrugated paper indicated at 8. Extending from one end of the strip 5 is a forked tongue 9 while extending from the

other end thereof is a spring strip 10 having a terminal eye 11 or other form of finger piece.

When attaching the device to a perch, a strip of paper indicated at 12 is laid upon the perch, after which a strip of corrugated 60 paper indicated at 8 is placed in the channel 7 and then on the paper strip 12. The forked tongue 9 is inserted under the head of the nail 2 and the spring strip 10 is placed in engagement with the hook 4. Thus the 65 trap is fastened securely to the perch and the fowls can roost thereon.

Vermin naturally hide in crevices and other inaccessible spaces and, consequently, will enter the spaces between the paper strip 70 12 and the corrugated strip 8. The strip 12 will prevent them from clinging to the perch 1. Therefore, by disengaging the strip 10 from the hook 4 and the tongue 9 from the nail 2, the strip 5 can be removed with the 75 paper strips 8 and 12 and said strips 8 and 12 with the vermin adhering thereto can be burnt or otherwise destroyed. Additional strips of paper can then be substituted and placed on the perch as before. 80

It has been found in practice that by providing a trap such as described, a perch can be kept reasonably clear of vermin.

What is claimed is:—

1. A vermin trap including a base strip of 85 paper or like material, a corrugated strip resting thereon, and a top strip bearing upon the base strip and housing the corrugated strip, said corrugated strip and base strip being removable from the top strip. 90

2. The combination with a perch and fastening devices outstanding therefrom, of a strip having a longitudinal channel in the bottom thereof, means upon the ends of the strip for detachably engaging said fastening 95 devices, a base strip extending under the channeled strip and resting on the perch, and a corrugated strip removably mounted in the channel and extending longitudinally thereof. 100

In testimony that I claim the foregoing as my own, I have hereto affixed my signature in the presence of two witnesses.

LELAND G. YOUNG.
